METHOD OF MAKING CUFFS.

No. 442,319.

Patented Dec. 9, 1890.

UNITED STATES PATENT OFFICE.

FRED B. IDE, OF TROY, NEW YORK, ASSIGNOR TO HENRY A. MERRITT, OF SAME PLACE.

METHOD OF MAKING CUFFS.

SPECIFICATION forming part of Letters Patent No. 442,319, dated December 9, 1890.

Application filed February 19, 1890. Serial No. 340,987. (No model.)

To all whom it may concern:

Be it known that I, FRED B. IDE, of the city of Troy, county of Rensselaer, and State of New York, have invented a new and useful Improvement in Apparel-Cuffs, of which the following is a specification.

My invention relates to improvements in the method of making apparel-cuffs; and these improvements have for their object to simplify the making of them and to reduce the cost of their production.

My invention consists (as will be more fully detailed hereinafter in connection with its illustration) in the application of two or more 15 ply-blanks cut of the same length as the exterior facings, and enough wider than the cuff to be made to form a hemfold in the side edge of each facing, and two or more plies cut about the same width as the cuff to be produced, 20 and the parts connected by placing at the bottom the two exterior facings, and over the latter the plies, then sewing the parts together across the ends, turning them through one of the open sides and then border-stitching the parts to finish them, my principal 25 improvement being in having what constitutes the outside facing of the cuff and the plies adjacently connected by the first end stitching, and not in placing the facings between the plies, then end stitching and turning the cuff out between the facings with part 30 of the plies attached to each of the facings. This change in the differing position of the facings and plies produces distinct square 35 corners and positions the exterior facing so as to be more easily laundered and to take on a better finish when the cuff is curled to give it body form.

Accompanying this specification to form a part of it there are two plates of drawings, 40 containing ten figures, illustrating my invention, with the same designation of parts by letter reference used in all of them.

Of the illustrations, Figure 1 shows the two 45 plies and the facing forming the outer face of the cuff as inclosed by a hemfold made in the facing. Fig. 2 shows the parts shown in Fig. 1 as laid over the facing, forming the exterior body-facing of the cuff. Fig. 3 shows

the parts as laid at Fig. 2 and end sewed. 50 Fig. 4 shows a longitudinal section of Fig. 3, taken on the line $x' x'$; and Fig. 5 shows a cross-section taken on the line $x^3 x^2$ of Fig. 3. Fig. 6 shows the parts connected, as at Fig. 3, after having been stitched across the ends 55 and ready for turning. Fig. 7 shows a section taken on the line $x^3 x^3$ of Fig. 6. Fig. 8 shows a completed cuff; Fig. 9, a section taken on the line $x^4 x^4$ of Fig. 8; and Fig. 10 shows a section taken on the line $x^5 x^5$ of 60 Fig. 8.

The several parts of the cuff thus illustrated are designated by letter reference and the step-by-step operations by which they are connected is described as follows:

The letter F' designates the facing that forms the exterior of the cuff when worn, and F^2 the facing that forms the body side of the cuff when worn, and $P' P^2$ designate the plies. The letters h' designate hemfolds formed in 70 the edge of the facing F' , embracing the side edges of the plies, and the letters h^2 designate the hemfolds formed in the edge of the facing F' , which do not embrace the edge of the plies, but are merely turned in 75 and secured by the border-stitching. The blanks thus cut and hemfolded, together with the plies, are laid as shown at Figs. 1 and 2, and are then end-stitched, as designated at S' , Figs. 3 and 4. They are then, as 80 in the position shown at Figs. 6 and 7, turned through either of the unsewed sides and border-stitched, as shown at S' , Figs. 8, 9, and 10. As thus made, the plies and what is the outer facing of the cuff when worn are 85 securely anchored together at the ends and at the sides by means of the hemfolds, while the inner or body side facing of the cuff does not embrace at its side edges the sides of the plies, so that in curling the cuffs for wearing 90 shape the inner facing will more readily take up any tendency to wrinkle.

Having thus described my invention, what I claim, and desire to secure by Letters Patent, is—

The method of making apparel-cuffs as herein described, and consisting of cutting the two exterior cuff-facings of same size,

hemfolding their side edges, placing the two facings together with their hemfolded edges reversed, with the hemfold of the facing forming the body side of the cuffs when worn embracing the edges of the ply placed over said facing, and then stitching the ends of the parts as laid, then turning them through one of the unclosed sides, so as to bring the facings outside, and then border-stitching the

ends and side edges, as and for the purposes to set forth.

Signed at Troy, New York, this 6th day of November, 1889, and in the presence of the two witnesses whose names are hereto written.

FRED B. IDE.

Witnesses:

W. E. HAGAN,

CHARLES S. BRINTNALL.
